US00D969350S

(12) **United States Design Patent** (10) **Patent No.:** **US D969,350 S**
(45) **Date of Patent:** **** Nov. 8, 2022**

- (54) **STRUCTURAL PANEL WITH AN ORNAMENTAL SURFACE**
- (71) Applicant: **Dongguan Shichang Metals Factory Ltd.**, DongGuan (CN)
- (72) Inventor: **Chen-Kang Lin**, DongGuan (CN)
- (73) Assignee: **Dongguan Shichang Metals Factory Ltd.**, DongGuan (CN)
- (**) Term: **15 Years**
- (21) Appl. No.: **29/778,011**
- (22) Filed: **Apr. 9, 2021**

Related U.S. Application Data

- (63) Continuation of application No. 29/716,783, filed on Dec. 12, 2019, now abandoned, which is a continuation-in-part of application No. 29/640,679, filed on Mar. 16, 2018, now Pat. No. Des. 884,487.

WO 2014186921 A1 11/2014

Primary Examiner — Catherine Ho*(74) Attorney, Agent, or Firm* — Luedeka Neely Group, P.C.

(57) **CLAIM**

The design for a structural panel with an ornamental surface, as shown and described.

DESCRIPTION

FIG. 1 is a right front perspective view of a structural panel with an ornamental surface showing my new design; FIG. 2 is a left front perspective view thereof; FIG. 3 is a right perspective view thereof; and, FIG. 4 is a top plan view thereof.

The area shown between the broken lines and the outer solid edge lines forms no part of the claimed design.

1 Claim, 4 Drawing Sheets
